UNITED STATES PATENT OFFICE

ROBERT HENRY DAVIS, OF LONDON, ENGLAND

SUBMARINE ESCAPE APPARATUS

Application filed February 18, 1932, Serial No. 593,909, and in Great Britain November 9, 1931.

This invention relates to submarine escape apparatus of the self-contained type comprising a flat panel-shaped breathing bag to be worn in a vertical position against the 5 chest of the wearer of the apparatus, a mouthpiece communicating with the breathing bag, means for absorbing carbon dioxide from the wearer's breath, so that the air in the breathing bag may be used over and over again, with or without means for admitting 10 a replenishing supply of oxygen or air or a mixture of oxygen and air, to the breathing bag, for example, an oxygen cylinder forming an integer of the outfit, these parts 15 being incorporated together to form a complete self-contained unit to be donned as such.

In the use of submarine escape outfits of this type, too rapid an ascent is often undesirable, as it may result in caisson illness due 20 to sudden change from exposure to high pressure at great depth to normal atmospheric pressure at the surface of the water. Moreover, in the case of self-contained breathing outfits of the type referred to, a 25 relatively slow ascent is desirable in that it permits any excess of air or oxygen in the breathing chamber of the apparatus to escape more freely and thus the pressure in the 30 chamber to equalize more approximately with the water pressure at the depth at which the wearer happens at any given moment to be submerged. When the pressure of the air or oxygen which is being breathed from 35 the breathing bag exceeds in any appreciable degree the pressure of the water, the wearer may suffer from a condition which prevents proper action of the respiratory organs and/or the circulatory system.

40 The aim of the present invention, therefore, is to incorporate in submarine escape outfits of the type referred to, means whereby the speed of the free or buoyancy ascent of the wearer through the water may be 45 checked.

In this connection, it will be appreciated 50 that in an escape outfit of the particular type to which the invention relates, there is but little upwardly directed surface available to present resistance to the water dur-

ing the buoyancy ascent of the wearer, owing to the flat panel form of the breathing bag and its position on the wearer when in use, and it is partly due to this fact that, as stated, the wearer's speed of ascent is frequently too 55 rapid.

It will further be understood that whilst of course, the area of resistance presented upwardly to the water by the outfit in position upon the wearer could be increased with 60 consequent increase of ascent-checking effect, by increasing the cross-sectional area of the breathing bag of the outfit, this method of meeting the difficulty would at once be impracticable, as it would be antithetical to 65 the general idea of compactness and minimization of overall back to front dimensions of the outfit. Thus, if the form of the breathing bag were altered from one of the usual flat 70 panel shape, to one of deep back-to-front dimension, besides the increase of cumbersomeness of the apparatus which this would entail, the wearer would not be able to work his way through manhole doors and like openings of 75 limited dimensions, for the protrusion before him of the breathing bag would operate as an obstruction to his passage.

It is essential, therefore, in submarine escape outfits of the type to which this invention relates, that the breathing bag shall 80 be of the flat panel form referred to, and the problem in the present invention has been to meet the ascent checking difficulty in a simple and efficient way, having in view this 85 particular consideration, as to the necessary flat form of the breathing bag, in conjunction with the many other important desiderata known to obtain in the use of a submarine escape outfit, for example, the requirement that every part of the outfit shall 90 be the acme of simplicity and foolproofness and yet thoroughly effective in operation, and the further requirement that any parts which have to be manipulated to operative position shall be capable of manipulation thereto with 95 the least possible effort and requirement of skill and in the least possible time, the conditions of use of a submarine escape outfit always being those of extreme emergency, 100 tending to cause distress and mental agita-

tion on the part of the person attempting to use the outfit.

According to the present invention, there is incorporated in a submarine escape outfit 5 of the type specified, a fin for checking the speed of buoyancy ascent of the wearer through the water, which fin is rollable or foldable from an operative position, in which it projects laterally from the general 10 external contour of the apparatus, to a stowage position snug against the wall of the breathing bag, in which it is substantially within said external contour.

According to a feature of the invention, 15 the fin may be adjustable to a plurality of speed-checking positions for the purpose of controlling at will its effect upon the ascent speed of the wearer. Thus, the fin may be adjustable selectively, to one or other of a 20 plurality of operative positions in which the fin is inclined to the horizontal, the particular position to which it is brought being determined in accordance with the degree to which the wearer desires to retard his ascent.

According to a further feature, the fin 25 may comprise an apron of flexible material attached in the apparatus by connecting means located along one edge of the apron, the latter being arranged to be held out in either a 30 horizontal or inclined position as the wearer of the apparatus ascends in the water.

According to another feature of the invention, the fin may be arranged to be held out 35 in its operative position by the hands of the wearer of the apparatus as he ascends in the water.

Alternatively, the fin may be combined in 40 the apparatus with means adapted to support it mechanically in the operative position either with the assistance of the hands of 45 the wearer or without.

In a simple and convenient construction 50 in accordance with the invention, in that form in which the fin comprises an apron of flexible material, the said apron may be connected along its free edge to a roller upon which it can be rolled up to a stowage position adjacent the attached edge of the apron and unrolled for use either fully or partially 55 according to the degree to which the wearer of the apparatus desires to retard his ascent, the roller preferably being provided for this purpose with handle portions at the two ends which project beyond the lateral edges of the apron.

According to another feature of the invention, the apron may be combined with a supporting stay or stays which are arranged to hold the apron out in its extended position, 60 being connected to the apron at or near its free edge either permanently or detachably, and are collapsible into a stowage position within or adjacent the general contour of the apparatus when the apron is not in use.

65 Various embodiments of the invention will

now be described by way of example, with reference to the accompanying drawings, which show the invention as applied to a self-contained breathing apparatus for submarine use, and of which:—

70 Figures 1 and 2 represent one form of the invention and show, respectively, the ascent-checking fin in its stowage or closed position (Figure 1) and in its open or operative position (Figure 2);

75 Figures 3 and 4 are corresponding views of another form of the invention;

80 Figure 5 represents still another form, with the ascent-checking fin in its operative position;

85 Figures 6 and 7 represent a further form of the invention, Figure 6 showing the fin in its stowage position and Figure 7 the fin in its operative position;

90 Figures 8 and 9 are corresponding views of yet another form of the invention.

Figure 10 illustrates a further arrangement, the ascent-checking fin being shown in its operative position;

95 Figures 11 and 12 illustrate another form, Figure 11 showing the fin in a position part-way between the stowage position and the operative position, and Figure 12, the fin in its fully extended or operative position;

Figures 13 and 14 illustrate another construction, and

Figures 15 and 16 yet a further construction.

Like reference characters indicate like parts in the various figures.

100 The self-contained breathing apparatus shown in the drawings and fitted with the ascent-checking fin in accordance with the invention, comprises a breathing bag 1 in the form of a collapsible rubber envelope, and a mouth-piece 2 to be worn upon the face of the user of the apparatus. The mouth-piece is connected to the breathing bag by means of a flexible breathing tube 3, and the

105 air which is exhaled through this breathing tube passes through a purifier situated within the breathing bag 1 before it enters the breathing bag. This purifier functions to extract carbon dioxide from the exhaled breath. Extending along the lower edge of the breathing bag 1 and supported therefrom in a strap 4, is an oxygen cylinder 5 in communication with the interior of the breathing bag 1 by way of a hand-operated

110 valve 6 and a conduit 7. The breathing bag and the parts attached thereto are arranged to hang from a neck-strap 8 in front of the wearer's chest, and to hold the apparatus in position snugly against the wearer's body, straps 9 are provided to extend around the

115 back of the wearer.

120 So far described, the apparatus is of the general known construction, and the construction is substantially the same in the

case of all of the several forms of the invention shown in the drawings.

In Figures 1 and 2, the ascent-checking fin comprises an apron 10 of flexible material, for example, waterproof canvas, anchored along its rear edge 11 to the forward bottom edge of the breathing bag 1 and attached along its forward edge to a roller 12 upon and by which it may be rolled up to the stowage position shown in Figure 1. For this purpose, the roller 12 is provided with handle-ports, as shown, which project at each end beyond the lateral edges of the apron.

To retain the rolled apron in its stowage position, straps 12 are provided, connected at one end to the bottom of the breathing bag 1 and fitted at the free end with one element of a snap fastener 14 or the like, the other element of which is mounted upon the face of the breathing bag. Obviously, any other convenient retaining means for the rolled apron may be provided. Also the apron, instead of being made of waterproof canvas, can be made of sheet rubber or any other suitable flexible material.

In use, the apron 10 is held out in the position shown in Figure 2 by the wearer of the apparatus as he ascends in the water, the wearer gripping the handle-ports of the roller 12, and, as will be appreciated, by varying the angle at which the apron is held to the horizontal, the extent to which the speed of the wearer's ascent through the water can be controlled.

Referring next to the form of the invention shown in Figures 3 and 4, in this case, the apparatus comprises an additional envelope 15 constituting a supplementary buoyancy chamber in accordance with the invention described in United States specification No. 582,623. This second envelope is of the flat form shown and is hingedly connected along its rear edge 16 to the front of the breathing bag 1 so as to occupy, at will, either the vertical position shown in Figure 3 or a horizontal position as shown in Figure 4.

In this latter position, the envelope operates as an ascent-checking fin in accordance with the present invention, in conjunction with an extension from the envelope in the form of an apron 18 of similar material to the apron 10 of the earlier construction. This apron 18 is attached along its rear edge to the free edge of the envelope 15 and, as in the earlier construction, it is mounted along its own free edge upon a roller 12, by and upon which it may be rolled up to the stowage position shown in Figure 3.

The envelope 15 is fitted interiorly with a small oxygen capsule 17, the neck of which can be readily broken by the wearer of the apparatus, when necessary, to inflate the chamber; this feature also is in accordance

with the arrangement described in the aforesaid application for Letters Patent.

In the arrangement shown in Figure 5, a supplementary buoyancy chamber 15 is provided in the same envelope as that which constitutes the breathing bag 1, the envelope being divided interiorly into two compartments by a horizontal partition 19. Moreover, in this arrangement, the supplementary buoyancy chamber is fitted with a non-return inflation inlet 20 by which the chamber may be inflated by means independent of the oxygen capsule 17, for example, by breath exhaled into the chamber by the wearer of the apparatus.

The ascent-checking fin in this construction shown in Figure 5, takes the form, as previously, of an apron 10 of flexible material mounted at its free edge upon a roller 12.

Figures 6 and 7 show another construction in accordance with the invention in which there is a supplementary buoyancy chamber additional to the breathing bag 1, but in this case, in contrast to the arrangement shown in Figures 3 and 4, the supplementary buoyancy chamber is fixedly connected to the face of the breathing bag, and the ascent-checking fin is constituted solely by an apron 10 of flexible material as in the construction first described.

Figures 8 and 9 illustrate an arrangement similar to that shown in Figures 1 and 2, but differing in this respect, that the apron 10 is arranged to be held out in this open position by means of struts 21. These struts are pivoted at their rear ends 22 to lugs or the like mounted upon the bottom of the breathing bag 1, and they are adapted to swing from an operative position, as shown in Figure 9, to the inoperative or stowage position, shown in Figure 8, in which latter position they lie more or less within the general contour of the apparatus. When the struts are in use (Figure 9) they engage the free edge of the apron 10 at their free ends by means of snap fasteners or the like 23, the male elements of which are mounted upon the tips of the struts, and the female elements upon the apron, or vice versa, as desired.

In this arrangement, as will be appreciated, the apron requires to be supported by the hands of the wearer against the pressure of the water as the wearer ascends, the handle portions of the roller 12 being gripped by the hands.

Figure 10 shows an alternative arrangement of supporting means for the apron 10, according to which, the apron is attached along its lateral edges to a pair of struts 24, the inner ends of which are pivoted to pins 25, slidable along a vertical slot-member 26 from the position shown in Figure 10 to a raised position near the top of the slot-member 26, at which raised position the struts 24, and with them the apron 10, occupy substantially vertical positions, the apron then

being in its stowage position. Co-operating with the struts 24 are a pair of inclined tie rods 27, which are pivoted at the upper end to the top of the slot-members 26 and at the lower end to the forward extremity of the struts 24. As the struts 24 collapse down to their inoperative positions, the tie rods 27 also collapse downwardly into one substantially common plane with the struts and the 10 apron 10.

Figures 11 and 12 show a further alternative arrangement, in which the apron 10 is arranged to be held out in its open position by a pair of horizontal folding arms 28, which 15 are pivoted at the inner end to lugs or the like mounted upon the bottom of the breathing bag 1 and are pivoted at their outer ends to the apron 10 near the free edge thereof, as shown. The joint between the two members 20 of the folding arms is combined with detent means adapted to hold the said members in alignment when the arms are in use. These detent means may take any convenient form. For example, they may comprise a shallow 25 projection 30 on one member, adapted to snap into a co-operating dent on the other member.

This form of the invention shown in Figures 11 and 12, like the form shown in Figures 8 and 9, is one in which the apron 10 is required to be held up against the pressure of the water by the hands of the wearer of the apparatus, the folding arms 28 serving simply to retain the apron 10 in its extended 35 position.

The arrangement shown in Figures 13 and 14 is one in which the apron 10 is supported in its operative position by folding arms 31 adapted not simply to hold the apron out 40 in its operative position, but also to support it against the pressure of the water as the wearer ascends. For this purpose, at each joint of the arms 31, one arm-member is formed along one of its edges, in the neighbourhood of the joint, with a short flange 32 which serves as an abutment for the corresponding edge of the adjacent arm-member on the opposite side of the joint, and the folding arms are hingedly connected to their attachment lugs 32 by hinges 33, the axes of 45 which are disposed vertically as shown.

In this construction, in contrast to that shown in Figures 11 and 12, the apron 10 is arranged to be rolled up upon a roller 12 to 50 the inoperative stowage position shown in Figure 13, and when the apron is in its extended or operative position, the ends of the roller 12 are held within notches 34 provided upon the extremities of the folding arms 31 55 to receive them.

When the parts are in their stowage positions, the folding arms 31 occupy the collapsed positions shown in Figure 13, that is to say, the several members of the folding 60 arms are folded over, the rearmost and the

one next to it edge to edge, and the outermost member face to face against the second member, and the collapsed arms are swung inwardly so as to overlap one another and to lie together within the general contour of the 70 apparatus.

In the construction shown in Figures 15 and 16, the fin comprises a sheet of waterproof canvas or other flexible material 35 attached along its rear edge to a frame rod 36 75 parallel to a hinge rod 36a and along its forward edge to a frame rod 37, the said rods 36, 36a and 37, being connected by a pair of folding arms 38, extending along the lateral edges of the sheet 35. The folding arms 38 80 are connected at the joint between their limbs by a second frame rod 39, the ends of which constitute the pivots of the said limbs of the arms 38.

The vane is swingably mounted in stationary lugs 32 to occupy either an operative position, as shown in Figure 16, or the inoperative collapsed position shown in Figure 15. In the collapsed position, the forward half of the fin is folded inwardly over the rear 90 half, as shown in Figure 15 and to assist in the operation of bringing the parts to their collapsed positions and in retaining them there, coiled springs 40 are provided upon the hinge rod 36a near the ends thereof, 95 the free extremities of these springs being bent into the form of a hook, and the hooked portion, as shown, engaging the under edge of the rear limbs of the folding arms 38. To resist the downward pressure of the water 100 upon the fin, as the wearer ascends, and prevent the said pressure from collapsing the fin, the forward limbs of the folding arms 38 are provided with rearward extension tongues 41, which abut the under edges of 105 the rear members of the arms so as to resist the bending of the arm at the joint.

It will be apparent that, although a number of different embodiments of the invention have been included in the foregoing description, the invention is susceptible to considerable variation in respect of the form of the ascent-checking fin and in regard to other details. For example, the fin, could comprise 110 a rigid flap hinged in the apparatus to swing from a stowage position in which it lies, say, against the front of the breathing bag, to an operative position in which it extends outwardly in a substantially horizontal plane. 115

What I claim is:—

1. A submarine escape outfit of the type specified, in which there is incorporated a fin for checking the speed of buoyancy ascent of the wearer through the water, which fin is 125 movable from an operative position in which it projects laterally from the general external contour of the outfit to a stowage position in which it lies snug against the wall of the breathing bag of the outfit, so as in this 130

position to be substantially within the general external contour of the outfit.

2. A submarine escape outfit of the type specified, in which there is incorporated a fin 5 for checking the speed of buoyancy ascent of the wearer through the water, which fin is movable from a stowage position in which it lies snug against the wall of the breathing bag of the outfit so as in this position to be 10 substantially within the general external contour of the apparatus, selectively to one or other of a plurality of speed-checking positions in which it projects laterally from said contour.

15 3. A submarine escape outfit of the type specified, and in accordance with claim 1, wherein the fin consists of an apron of flexible material anchored in the outfit along its rear edge and collapsible upon itself to the 20 stowage position.

4. A submarine escape outfit of the type specified and in accordance with claim 1, wherein the fin consists of an apron of flexible material anchored in the outfit along its 25 rear edge and attached along its forward edge to a roller upon which it may be rolled up to the stowage position.

5. A submarine escape outfit of the type specified and in accordance with claim 1, 30 wherein the fin consists of an apron of flexible material, anchored in the outfit along its rear edge, arranged to be held out in the operative position by the hands of the wearer of the outfit as he ascends in the water and 35 attached along its forward edge to a roller upon which it may be rolled up to the stowage position.

6. A submarine escape outfit of the type specified and in accordance with claim 1, 40 wherein the fin consists of an apron of flexible material, anchored in the outfit along its rear edge, adapted to be held out at any desired angle, so as to project laterally from the general external contour of the outfit, by 45 the hands of the wearer of the outfit as he ascends in the water and attached along its forward edge to a roller upon which it may be rolled up to the stowage position.

7. A submarine escape outfit of the type 50 specified and in accordance with claim 1, wherein the fin is combined in the apparatus with means adapted to support it mechanically in the operative position.

8. A submarine escape outfit of the type 55 specified and in accordance with claim 1, wherein the fin consists of an apron of flexible material anchored in the outfit along its rear edge and attached along its forward edge to a roller upon which it may be rolled 60 up to the stowage position, in combination with foldable arms which are hingedly connected at their inner ends to a rigid part of the outfit to swing in a substantially horizontal plane to and from an operative position 65 in which they afford support to the apron,

both in a direction parallel to its general plane so as to hold the apron open and also in a direction perpendicular to said plane.

9. A submarine escape outfit of the type specified, in which there is incorporated a supplemental buoyancy chamber in the form of a flat inflatable envelope hingedly connected to the breathing bag of the outfit so as to occupy at will either a position in which it hangs vertically against the face of the breathing bag or a position in which it projects laterally from said face so as to serve as a fin to check the spread of the buoyancy ascent of the wearer, in combination with an apron of flexible material attached along the rear edge to free the edge of the supplemental buoyancy chamber and adapted to be held out by the hands of the wearer of the outfit in alignment with said chamber when the latter is in its ascent-checking position. 70 75 80

10. A submarine escape outfit of the type specified and in accordance with claim 1, wherein the fin consists of an apron of flexible material, anchored in the outfit along its rear edge, arranged to be held out at any desired angle, so as to project laterally from the general external contour of the outfit, solely by the hands of the wearer of the outfit as he ascends in the water and attached along its forward edge to a roller upon which it may be rolled up to the stowage position. 90 95

11. A submarine escape outfit of the type specified and in accordance with claim 1, wherein the fin consists of a sheet of flexible material mounted upon a frame which is foldable upon itself about an axis intermediate the forward and rear edges of the fin and is hingedly mounted in the outfit to swing when folded into an inoperative position snug against the general external contour of the outfit, in combination with spring control means tending to move the fin to said inoperative position. 100 105
